UNITED STATES PATENT OFFICE

2,019,881

WRINGER FOR WASHING MACHINES

Carl C. Weisbrod, Newton, Iowa, assignor to One
Minute Washer Company, Newton, Iowa, a cor-
poration of Iowa

Application October 16, 1933, Serial No. 693,786

7 Claims. (Cl. 68—32)

The object of my invention is to provide a wringer for washing machines of very simple, durable and inexpensive construction.

More particularly, it is my object to provide a wringer structure having certain of the features of the Perkins patent, No. 1,902,580, which has certain advantages thereover, particularly in the provision of a replaceable bearing for the lower wringer shaft and the particular means for preventing the clutching of the wringer mechanism with a driving shaft during the swinging of the wringer from one position to another and the provision of a protector for the upper wringer roll, and in the provision of anti-friction devices adapted to engage with a minimum of wear when the upper wringer roll is swung to clutching position.

Another object is to provide novel means for moving the upper wringer roll from one position to another.

With these and other objects in view, my invention consists in the construction, arrangement and combination of the various parts of my wringer for washing machines, whereby the objects contemplated are attained, as hereinafter more fully set forth, pointed out in my claims, and illustrated in the accompanying drawings, in which:

Figure 1 is a front elevation of a wringer structure embodying my invention.

Figure 1-A is an elevation of the cam block, which cooperates with the upper wringer roll.

Figure 2 is a vertical, detailed, sectional view taken on the line 2—2 of Figure 1.

Figure 3 is a perspective view of the slotted cap used on the wringer head.

Figure 4 is a detailed, sectional view taken on the line 4—4 of Figure 1; and

Figure 5 is a similar view taken on the line 5—5 of Figure 1.

In the accompanying drawings, I have used the reference numeral 10 to indicate generally a tub. At the side of the tub is an upright tube or sleeve 11 through which extends a shaft 12 operated from any suitable source of power, and which forms the driving shaft for the wringer mechanism.

Supported on the sleeve 11 is a sleeve 13 fastened to the tub 10 by means of a bracket 14. The lower part of the sleeve 13 fits snugly on the sleeve 11 and the upper part at 13a is diametrically spaced therefrom.

Supported on the sleeve 11 is what I will call the wringer head A, which in turn supports the wringer frame B. The wringer head A comprises

a horizontal tubular member 15 closed at one end, as at 16, and having a tubular downward extension 17 telescopically receiving the sleeve 11 and partially telescopically received in the upper end of the sleeve 13.

I preferably interpose between the tubular sleeve 17 and the sleeve 11, the bronze bushings 18 and 19.

The wringer head and wringer are mounted to swing around the tube 11, which might be called a 16 post, so that the wringer may be positioned over the tub 10 or over other tubs or the like, depending upon its position with relation to the tube or sleeve 11.

The upper end of the shaft 12 is squared as at 15 20 and has non-rotatably mounted on it a beveled gear 21. A suitable bushing 22 is interposed between the hub of the gear 21 and the wall of the sleeve 17.

Received within the sleeve portion 15 of the 20 wringer head A spaced from the closed end 16 thereof is an annular ring or the like 23, which is arranged for limited movement longitudinally of the sleeve 15 and for limited rotary movement.

A screw 24 extends upwardly from the ring 23 26 through a slot 25 in the sleeve 15, and travels in the S-shaped slot 26 (Figures 1 and 3) in the cam plate 27 detachably mounted by means of screws or the like on the sleeve 15 by means of screws 28 extended through the holes 29 in the 20 cam plate and into suitable threaded openings in the sleeve 15.

The cam plate 27 is of such material and so arranged that it may be curved end to end to fit in position and may be bent in either direction, so that if desired, it may be turned end for end and turned over so as to thus reverse its operation for adapting it for any difference in direction of the rotation of the driving shaft. There may be provided a cover plate 30 for the cam plate.

The ring 23 may be rotated and slid longitudinally to the extent permitted by the movement of the head of the screw 25 in the slot 26 by means 45 hereinafter referred to.

It will be seen that the slot 26 is so constructed that when the ring 23 is moved lengthwise of the sleeve 15, the travel of the screw 25 in the slot 26 will cause the ring 23 to be so moved lengthwise of the sleeve 15.

The purpose of this movement of the ring 23 lengthwise in the sleeve 15 is to effect clutching action as hereinafter mentioned.

When the screw head is in the central part of 55

the slot 26 the clutch members are in neutral position.

The ring 23 has in its lower part a recess 31, which when the parts are in neutral position just mentioned registers with the detent rod 32 (Figure 1) slidably mounted in the apron 33 formed on the sleeve 17.

In the lower end of the detent rod is a head 34. A spring 35 normally tends to keep the detent rod in its lower position. The upper part of the sleeve portion 13a is provided with recesses 36. When the head 34 is in one of those recesses, the wringer is held in one of its various positions and can not be swung therefrom.

15 In order to swing the wringer around the sleeve 11, the operator must grasp the lever 37 and raise the detent rod 32 for lifting the head 34 out of one of the recesses 36. This can only be done when the clutch parts are in neutral position and the recess 31 is in line with the rod 32 to permit the upper end of the rod to travel in the recess 31.

After the wringer is swung around, the head 34 slides on the upper edge of the sleeve portion 13a and the wringer can not be thrown into gear until the head reaches another notch 36 when the spring 35 will force it downwardly and withdraw the rod 32 from the recess 31.

A tubular shaft 38 is journaled in a bearing 39 in the closed end of the wringer head A and in the ring 23. The shaft 38 is slidable and has fixed on it the beveled gears 40 and 41 and their connecting sleeve 42. The shaft 38 must slide with the ring 23 because the beveled gear 41 abuts against the sleeve 25 on one side thereof, and the shaft 38 has an annular flange 43 engaging the opposite side of the ring 23.

The lower wringer roll 44 has a shaft 45. We show the bearing at one end only of the shaft 45, but it will be understood that the bearing at the other end is the same.

The shaft end has an ordinary bushing or the like 46, which is received in a removable bearing 47, which has a cylindrical bore and is squared in its external sectional outline as illustrated in Figure 4 and is seated in an angular bearing socket 48 formed in the wringer frame.

The main pressure on the lower wringer roll bearings is downward and it would be observed that the bearing 47, if it should become worn, may be given a quarter turn, for thus increasing its life.

The left-hand end of the shaft 45 as shown in Figure 1 is received in one end of a sleeve 49 and is fixed thereto.

Mounted on the shaft 38 is a cross pin 50, best shown in Figure 5, on which are anti-friction rollers 51. The pin 50 and rollers 51 are slidably received in an elongated slot 52 in the end of the sleeve 49 opposite the shaft 45. Thus the shaft 45 can be rotated from the shaft 38 and yet the sliding movement of the shaft 38 and the connected parts is permitted.

At each end of the wringer frame B in the upper part thereof, there is provided above the bearing socket 48 the oppositely extending shoulders 54. Resting on the shoulders 54 is a cam block or the like 55, the inner face of which is shown in Figure 1-A. At its upper end, each cam block 55 has an inwardly projecting flange 56. From one side only of the cam block 55, there extends downwardly a flange 57. A lug 58 extends from each flange 57 inwardly lengthwise of the wringer frame. The cam block 55 above the lower end of the flange 57 is substan-

tially narrower than the casing frame B from front to rear and narrower than the cap 59 as shown in Figure 4. Below the flange 57, the cam block 55 is wider and extends laterally to the side walls of the casing B.

Below the flange 57 at each side edge of the cam block 55 is a flange 60 extending close to the wall of the casing B lengthwise of the wringer frame.

At the lower end of each flange 60 is a laterally projecting internally-apertured and threaded lug 61. The upper ends of the tension bolts 62 are threaded into the lugs 61 and project downwardly through the shoulders 54. (Figure 4). The lugs 61 preferably rest on washers 63. On the lower ends of the tension bolts 62 are the nuts 64. On each bolt 62 is a coil spring 65 between the nuts 64 and the shoulder 54. Thus the cam block 55 is held down under spring tension, but may be moved upwardly slightly against the tension of the springs 65.

Formed on the cam blocks below the lower end of the flange 57 and connected with the flanges 60 are lugs 66 which project laterally toward each other as shown in Figure 4 and the under inner edges of which are inclined at 67 for functioning as hereinafter described.

Mounted on the cam blocks 55 above the inner ends of the respective lugs 66 are laterally spaced anti-friction rollers 68.

It may be mentioned at this point that the caps 59 are connected to the cam blocks 55 by means of angle brackets 69 (Figure 4). One arm of each angle bracket 69 is fastened by a screw or the like 70 to the lug 58 and has in its other angle a vertically elongated slot 71, which receives a pin 72 extending inwardly from the wall of the cap 59.

The parts are arranged in such manner that the cap may be lifted slightly, thus raising the pin 72 in the slot 71, whereupon the cap may be tilted over for allowing access to the parts below it and for permitting removal of the parts.

The upper wringer roll 13 has a shaft 74, which projects from the ends of the roll proper, and has on it the bushings 75. Each end of the shaft 74 and each bushing 75 is journaled in a bearing 76 formed on a casting 77.

Formed on the casting 77 above the bearing 76 is a bearing 78 in which is journaled the shaft 79. On the shaft 78 is a roller 80 on substantially the same vertical plane as the rollers 68.

The parts are so arranged that by swinging the upper wringer roll 13 bodily laterally, the clutch mechanism can be operated.

When the upper wringer roll is immediately above the lower wringer roll, the parts are in neutral position.

For controlling the upper wringer roll, I provide a clutch and release bar 81, having the handle 82, and having generally the form of a downwardly opening channel, formed with caps 83 at its ends to snugly receive the upper portions of the castings 77.

For affording the operative relation between the upper wringer roll and the clutch mechanism, I provide at the left end only of the wringer structure shown in Figure 1, the yoke 84 receiving between its arms the bearing 78.

At its lower part, the yoke 84 is curved toward the wringer head and is connected with an annular ring 85 journaled in a suitable opening 86 in the wringer frame B. (See Figures 1, 4 and 5.)

Projecting toward the wringer head from the ring 85 are a pair of pins 87, which slide in

suitable holes 88 in the ring 23 (see Figures 1 and 5).

In the edge of the ring 85 are three notches 89 arranged to coact with a spring-pressed detent ball 90. The ball 90 and the spring 91, which tends to press it toward the ring 85, are received in a hole 92 in the end wall of the wringer frame B, in line with the opening 86 in which the ring 85 rotates. The notches 89 are so located as to permit the detent ball to tend to hold the parts in place when the upper wringer roll is swung to neutral position or to position for placing either of the gears 40—41 in mesh with the gear 21.

15 A drain board 93 has at its ends up-turned flanges 94 journaled on the ends of screw pins 95, projected through the end walls of the casting of the wringer frame B.

20 The left-hand screw pin 95 also holds the spring 91 in place.

At the left-hand end of the drain board 93, it has an arm 96 extending upwardly, bifurcated at its upper end, to receive the pin 97 projecting from the ring 85. This is for the purpose of furnishing means for tilting the drain board 93 according to the position of the upper wringer roll.

25 For furnishing additional protection, I have extended between the upper parts of the castings 77 between the caps 83 a rod 98 on which is loosely supported a roll protecting cap 99 (see Figures 1 and 2).

Operation

30 It will have been observed that the wringer head A is rotatably supported on the upstanding sleeve 11, so as to permit the head and the wringer proper supported thereby to swing on a vertical axis at the center of the sleeve 11.

40 The head A is bolted or screwed to the wringer frame B in any suitable manner. The proper wringer frame end has the hole 88 in which the ring 85 rotates and which affords means for the insertion of the mechanism connecting the wringer proper with the mechanism in the head.

45 It will, of course, be understood that the sleeve 49 hereinbefore referred to projects through the hole in the center of the ring 85.

50 The parts are so constructed and arranged that the upper wringer roll 73 may be swung from position immediately above the wringer roll 44 laterally in either direction for operating the clutch and thus causing the wringer rolls to be operated in one direction or to be operated in the reverse direction. For example, if the operator grasps the handle 82 of the clutch control and release bar 81 and swings it from its neutral position shown in Figures 1 and 4 toward the left as shown in Figure 4, the clutch members will be connected. This would mean that the operator standing facing the wringer shown in Figure 1 would pull the handle toward him. The caps 83 engaging the upper ends of the castings 77 would tend to pull the rollers 80 from position shown in full lines in Figure 4 toward the dotted line position shown in that figure, and the wringer roll 73 would be swung from its full line position shown in Figure 4 toward its dotted line position shown therein.

70 The bearings 76 (Figure 1) will engage the inclined faces 67 of the lugs 66 (Figure 4) and the rollers 80 would engage the left-hand rollers 68 (Figure 4) so that if the upper wringer roll is forced to clutching position, the rollers 80 and 68 afford anti-friction means which greatly

reduces the wear, which I have found to otherwise occur where two cam surfaces are slid together or where a roller is caused to travel over one fixed surface. The adjustable set screws 100 in the lugs 66 engage the rollers 80 and thus limit the swinging movement of the upper wringer roll.

I might mention at this time that when the roller is swung to its position shown by dotted lines in Figure 4, the clothes are fed in from the left 10 and the pressure of the wringing operation is such that the upper wringer roll will retain its then assumed position during the wringing operation. When the upper roll is thus swung laterally, the yoke 84 is also swung for rotating the ring 85. 15 The pins 87 projecting from the ring 85 into the ring 23 serve to thus rotate the ring 23 for a limited distance, causing the head of the screw 24 to travel in the slot 26 and to move the ring 23 and the shaft 38 lengthwise for throwing the 20 clutch into gear. Whether the gear 40 or the gear 41 is the one thrown into connection with the gear 21 depends upon whether the roll 73 is moved laterally one way or laterally the other way. 25

The detent ball 90 helps to hold the parts in position when they have been moved for connecting the clutch members and when they are in control.

If it is desired to swing the wringer from one 30 position around the sleeve 11 to another position, it will be observed that normally when the wringer is in wringing position, the head 34 on the detent rod 32 will project into one of the recesses 36, so that the wringer can not be swung 35 around the sleeve 11.

When it is desired to swing the wringer, the clutch structure must be moved to neutral position, so that the handle 37 may be grasped for raising the detent rod 32 for bringing its upper 40 end into the recess 31. The handle must be held until the swinging movement of the wringer has started. Then the head 34 will slide on the upper edge of the member 13a until the next recess 36 is reached. Thereupon the spring 35 45 will force the head 34 into such next recess 36.

Then the wringer can be thrown from control for operating the clutch to rotate the wringer rolls in either direction desired.

If it is desired to swing the wringer further, the 50 handle 37 must again be operated to raise the detent rod 32.

At the present time, I consider the most important feature of my invention to be the provision of the anti-friction means which reduces the 55 wear on the cam plate to a minimum. This I have found to be of almost vital importance in a wringer of this type. The upper wringer shaft can roll on the cam faces with which it coacts and the use of the rollers 80 and 68 reduces the 60 wear on the cam plate to a minimum.

It will, of course, be obvious from the foregoing description that when the wringer is in operative position and the clutch members are engaged, if any trouble occurs the operator by a simple push 65 on the bar 81 will move the parts to where the clutch is in neutral and the operation of the wringer will be stopped.

The bar 81 with its cap members 83 at the end affords a means for operating the casing or bearing bracket 77 and also functions as a quick clutch release and also serves as a means for holding the rod 98 in place.

It will be observed that structure has been provided which is convenient for the removal of 75

the upper wringer roll. The clutch and release bar 81 may be removed by simply lifting it upwardly. Then by tilting the caps 56 on their pivot pins 72, the upper wringer roll can be lifted, 5 and by swinging the roller 80 laterally until it clears the flange 56 (see Figures 1 and 4), the upper wringer roll can be lifted bodily out of the frame.

It will also be observed that it is an easy matter 10 to remove the lower wringer roll from the frame.

All of this, of course, makes for convenience in assembling and installing the parts.

It is my purpose to cover by my claims any 15 modifications of structure, which may be included within their scope and within the scope of my invention.

I claim as my invention:

1. In a wringer structure including a frame, a 20 wringer head connected therewith, a driving mechanism in the wringer head including clutch means mounted on a tubular shaft, said shaft being longitudinally slideable, a lower wringer roll journaled in said frame, a tubular sleeve-like shaft fixed with the lower wringer roll projecting 25 into said tubular shaft, being of less diameter than the sliding shaft and having an elongated slot in its end, a pin carried by the slideable shaft and extended through said slot, and an anti-friction means on said pin for engaging the walls of 30 the slot.

2. A wringer structure including a frame, a wringer roll journaled in the lower part of the frame, an upper wringer roll having projecting shaft ends, means for supporting the upper wringer roll for limited bodily movement around the lower roll, a cam plate supported at each end of the frame having laterally spaced inclined cams and laterally spaced rollers, castings or bearing brackets at the opposite ends of the upper roll, 40 having the upper roll shaft journaled therein and projecting therefrom and having rollers supported thereon, whereby when said brackets are rocked, the rollers thereon selectively engage rollers on the cam plate and the upper wringer shaft 45 ends are moved into engagement selectively with cams on the cam plate, means actuated by the bodily movement of the upper wringer roll for operatively connecting the wringer with a driving shaft, and the wear on the cam plate parts 50 due to the shifting of the upper wringer roll is thus reduced to a minimum.

3. In a structure of the kind described, a wringer frame, a lower wringer roll journaled therein, an upper wringer roll having projecting shaft 55 ends, means for supporting the upper wringer roll for allowing it limited bodily movement around the lower roll, and means for adjusting the upper wringer roll to various positions, including a bearing bracket having said shaft ends journaled therein, and upwardly projecting portions, a release bar having at its ends caps for snugly receiving said upwardly projecting portions, whereby when the bar is moved laterally the upper wringer roll can be moved around the lower wringer roll.

4. In a structure of the kind described, a wringer frame, a lower wringer roll journaled therein,

an upper wringer roll having projecting shaft ends, means for supporting the upper wringer roll for allowing it limited bodily movement around the lower roll, and means for adjusting the upper wringer roll to various positions, including a bearing bracket having said shaft ends journaled therein, and upwardly projecting portions, a release bar having at its ends caps for snugly receiving said upwardly projecting portions, whereby when the bar is moved laterally the upper wringer roll can be moved around the lower wringer roll, a shaft extending through said upwardly projecting portions and held against lengthwise movement by said caps, and a protector supported on said shaft and extending downwardly over the upper portion of said upper wringer roll. 5

5. In a wringer structure, a frame having upright members at its ends formed with end and side walls, movable caps for the tops of said upright end portions, cam plates in the upright end 20 portions of the frame, an upper wringer roll having projecting shaft ends, bearing plates having said ends journaled therein, and carrying means for cooperating with the ends of the shafts engaging the cam plates, flanges on the upper parts 25 of the cam plates for limiting the upward movement of the bearing plates but for permitting the bearing plates and the upper wringer roll to be lifted out of the frame by imparting to them slight lateral movement, and a release bar seated 30 on the bearing plates and removable therefrom by vertical upward movement.

6. In a structure of the kind described, a wringer frame, a lower wringer roll journaled therein, an upper wringer roll having projecting shaft 35 ends, means for supporting the upper wringer roll for allowing it limited bodily movement around the lower roll, said means including yokes receiving the shaft ends, and having portions journaled in the frame, means for imparting rotation 40 to the lower wringer roll, including a clutch structure adapted to stand in neutral or in different clutched positions for rotating the lower wringer roll in opposite directions, a portion of one yoke, which is journaled in the frame, having spaced 45 notches, and a spring-pressed detent for coacting with said notches for tending to hold said last-named yoke portion either in neutral or either of its clutching positions.

7. In a structure of the kind described, a wringer frame, a lower wringer roll journaled therein, an upper wringer roll mounted to have limited bodily movement around the lower roll, means for imparting rotation to the lower roll, including a clutch structure having a bodily movable slideable portion, means for operatively connecting the upper wringer roll with said bodily slideable portion, whereby the movement of the upper wringer roll around the lower wringer roll serves to slide said portion, said means including a normally fixed plate capable of removal and provided with a cam slot, said slideable portion having a member for coacting with said slot, said plate being capable of being fitted in place with either face up and of being turned end to end. 60 65

CARL C. WEISBROD.
